UNITED STATES PATENT OFFICE.

BIRNEY C. BATCHELLER, OF PHILADELPHIA, PENNSYLVANIA.

SENDING DEVICE FOR PNEUMATIC-DESPATCH SYSTEMS.

SPECIFICATION forming part of Letters Patent No. 777,328, dated December 13, 1904.

Application filed March 29, 1901. Serial No. 53,406. (No model.)

To all whom it may concern:

Be it known that I, BIRNEY C. BATCHELLER, a citizen of the United States of America, residing in the city and county of Philadelphia, 5 in the State of Pennsylvania, have invented a certain new and useful Improvement in Sending Devices for Pneumatic-Despatch Systems, of which the following is a true and exact description, reference being had to the accompanying drawings, which form a part thereof.

My invention relates to pneumatic-despatch systems, and has for its object to provide a sending device of a peculiarly simple and efficient character.

The particular kind of system to which my invention relates is one in which the tube through which the carriers are sent is normally open and without air-current and in which a current of air is admitted to the receiving end of the pipe after the carrier is introduced therein and maintained for a sufficient length of time to propel the carrier to the delivery end; and my invention consists in a novel series of connected appliances by 20 means of which the single motion of a lever closes the receiving end of the pipe, opens a passage thereto from an air-conduit, and sets in operation mechanism whereby the tube is kept closed and the air-current admitted thereto for a determined length of time and then the tube automatically opened and the air-current cut off therefrom.

The nature of my improvements will be best understood as described in connection with the drawings, which illustrate my invention in what I believe to be its best and most practicable form, and in which—

Figure 1 is a side elevation, shown partly in section, on the line 1 1 of Fig. 2. Fig. 2 is a 40 horizontal section taken on the line 2 2 of Fig. 1. Fig. 3 is a vertical section through the receiving end of the tube with its immediate connections shown partly on the section-line 3 3 of Fig. 4, and Fig. 4 is a vertical section on the line 4 4 of Fig. 1.

A indicates a tubular casting forming the receiving end of the tube. It is preferably made with a terminal section of enlarged diameter, as indicated at A', said enlarged portion having a longitudinal opening A² lead-

ing into the air-chamber (indicated at B) and which in the construction shown is formed of the same casting as the tube end A. The outer end of the tubular casting A, as shown, is made of still greater diameter (see A³) and internally threaded, a³ indicating an externally-threaded annular ring which screws into this threaded portion. 55

A⁴ indicates the inner end of the tubular casting, into which fits the transmission-tube P.

A⁵ indicates a bracket serving as a hinge-bearing for the lid or gate.

A⁶ is a bracket serving to support the pivot for the actuating-lever. 65

A⁷ indicates the pivot supporting the bracket for the latching devices to be described.

A⁸ indicates an extension of the casting terminating in the oppositely-extending arms A¹⁰ A¹¹, which support, respectively, the perforated guide A¹², the internal bore of which is indicated at a¹² and the annular internally-threaded hub indicated at A¹³, a¹³ indicating its internal bore. 70

A⁹ indicates a portion of the casting to 75 which is secured the guide-plate H.

B, as already stated, is the air-chamber, divided into two compartments B' and B² by the valve-seated portion B³. The chamber B' communicates with the tube-head A through the opening A², already described, and has a perforation B⁴, which serves as a guide for the piston-rod E'. The chamber B² has an open end closed by a head B⁵, having in it a guide B⁶ for the opposite end of the piston-rod. 80 This chamber has also a lateral opening B⁷, to which is connected the air-pipe Q. 85

C is a sleeve of substantially the internal diameter of the pneumatic tube, this sleeve fitting in the enlarged portion A' of the casting and having a slot C', which can be made to register more or less with a slotted opening A², so as to regulate the opening between the air-chamber B' and the head of the pneumatic tube. The sleeve C is, as shown, provided with an outer lip C⁸, against which the gate fits, and with an annular flange C⁹, which fits into the terminal enlargement A³ of the tube-head and is clamped in place by a threaded annulus a³. 90 95 100

D indicates the gate for closing the end of the pneumatic tube, the gate being in the construction shown hinged by an arm D³ to the bracket A⁵, formed with an outer rib or projection D' of a substantially segmental form, said segment being of such shape as would correspond when the gate is closed with that of a circle drawn from the pivot-point of the actuating-lever. At the rear of this rib or projection D' the gate is provided with the heel extension D² for the purpose hereinafter described.

E is a valve normally seated on the portion B³ and closing the connection between the chambers B' and B³. From the front of this valve extends the piston-rod or valve-rod E', working through the perforation B⁴, and from its rear extends the rod E², guided in the perforation B⁶.

E³ indicates a spring acting to hold the valve to its seat.

F is a lever pivoted on the bracket A⁶ by the pin f. As shown, it is provided with an enlargement F', which operates against the end of the valve-rod E'. The lever is also provided with a projecting pin F², carrying, as shown, a roller f², which extends over the gate, F³ indicating the handle of the lever.

F⁴ indicates a spring acting to move and hold the lever in a direction to open the gate and to recede from the valve-rod E'.

H is a guide-plate for the lever secured at its ends to the portion A⁸ of the casting and to the side of the tube end.

G is a latch pivoted at G² and adapted to engage and hold the lever in the position shown in Fig. 1. The latch is thrown into engaging position by the action of a spring G³ and is provided with a rearward extension G', by means of which it is disengaged with the mechanism to be described.

I and I' indicate flanged metal caps adapted to be secured together by their outer flanges, so as to form a chamber in which is situated the diaphragm J. The lower section I is clamped against the head A¹² by means of the threaded plug I², formed with a central perforation, and this lower section is also formed with a perforation I³, with which an air-pipe M communicates, the opposite end of the pipe entering the air-chamber B³ through the lateral opening B⁸. The upper section I' is formed with perforations I⁴ and I⁵. The diaphragm J is by means of plates J' and J², which clamp its central portion between them, secured to the head K' of a dependent rod K, K² indicating a nut by which the plates J' and J² are clamped against the head K'. The rod K has a threaded portion K³, by means of

which it is secured to a head L, having a terminal flange L', a prolongation of the rod K (indicated at K⁴) extending through the guide A¹². In the perforation I⁴ is screwed the perforated plug O, having a threaded cross-bar O², in which works the adjusting-screw O⁴ of

a needle-valve O³, O⁵ indicating the handle by which the valve is adjusted and O' the perforation in the plug O in which the valve works.

N indicates a sleeve which is secured in the perforation I⁶ and has at its lower end a valve-seat normally closed by a valve N', N² indicating the upwardly-extending valve-stem having a head N³, against which the spring N⁴ works to hold the valve to its seat.

The operation of my device is readily followed. Normally the lever F is in non-operative position, the gate D open, the valve E closed, and the diaphragm J and head L in the position shown in Fig. 1. A carrier is then inserted in the tube-head A and the lever F moved to the position shown in Fig. 1, this motion of the lever first closing the gate D and then the roller F², moving over the segment D', holding the gate closed, while the enlargement F' presses against the valve-rod E' and opens the valve E, permitting air to pass from the chamber B² to the chamber B' and thence through the slots A² and C' into the tube-head A' and thence through the tube, propelling the carrier with it. As soon as the lever F is moved to the position shown in Fig. 1 the latch G engages it, as shown, holding it in that position, and as soon as the valve E is opened the air entering the chamber B' passes through the pipe M into the lower part of the diaphragm-chamber, moving the diaphragm up with a speed which corresponds to the escape of air from the upper part of the chamber through the orifice O', this air escape being nicely regulated by the needle-valve O³. The upward motion of the diaphragm carries with it the rod K and the flanged head L, and toward the end of the upward movement of these parts the flange L' comes in contact with the latch G' of the latch-lever and through it moves the latch G to a position in which it disengages the lever F, which is immediately thrust to non-operative position by its spring F⁴, the valve E closing and the gate D being opened by the impingement of the roller D² against the heel of the heel extension D². The closing of the valve E cuts off the supply of air to the diaphragm-chamber, the lower portion of which exhausts freely into the open-ended tube, and the diaphragm and dependent parts move rapidly to normal position as the air is permitted to enter freely into the upper part of the chamber through the valve N', which is held to its seat by only a slight spring-pressure.

Having now described my invention, what I claim as new, and desire to secure by Letters Patent, is—

In a pneumatic-despatch system, a sender comprising an open-ended tube in combination with a hinged gate for closing the end of said tube having a heel extension D³ and a substantially segmental rear extension D', an air-conduit leading into the tube, a normally closed air-valve for closing the connection be-

tween the tube and the air-conduit, a hand-lever pivoted at a point substantially corresponding with the center of the segment D' when the gate is closed and having a projection adapted to press against said segment when moved in one direction and against the heel D² when moved in the other direction, means tending to move the lever toward the heel extension D², a latch for holding the lever 5 in the position where it presses against the segment D' and holds the gate closed and an 10

air-valve-opening device arranged to be actuated by the movement of the lever to close the gate and to close when the lever is retracted, a time-escapement set in operation by the 15 movement of the lever to close the gate and operating to release the latch.

BIRNEY C. BATCHELLER.
